UNITED STATES PATENT OFFICE.

CHARLES C. BADEAU, OF SWISSVALE, PENNSYLVANIA, ASSIGNOR TO SWITCHBOARD EQUIPMENT COMPANY, OF PITTSBURG, PENNSYLVANIA, A CORPORATION OF PENNSYLVANIA.

CIRCUIT-OPENER.

976,838.

Specification of Letters Patent. Patented Nov. 29, 1910.

Application filed April 27, 1905. Serial No. 257,783.

To all whom it may concern:

Be it known that I, CHARLES C. BADEAU, of Swissvale, in the county of Allegheny and State of Pennsylvania, have invented a 5 certain new and useful Circuit-Opener, of which the following is a full, clear, and exact description, reference being had to the accompanying drawings, forming part of this specification, in which—

10 Figure 1 is a side elevation, partly in section, illustrating a circuit opener, embodying my invention; Fig. 2 is a plan view of the same; Fig. 3 is a longitudinal, vertical sectional view; Fig. 4 is an end view viewed 15 from the right-hand of Fig. 1; Fig. 5 is an end view viewed from the left-hand end of Fig. 1; and Fig. 6 is a cross-sectional view through the coil.

In all of these views, the circuit opener is 20 shown in its closed position.

My invention relates to that class of circuit openers that are provided with contact members, and a handle for opening and closing the contact. It may also be provided 25 with means for automatically breaking the circuit, whenever the circuit becomes overcharged.

It consists in devices for lessening the friction, for making a more perfect contact, 30 and for lessening the danger of injury to the contact members.

I will now describe my invention so that others skilled in the art to which it appertains may manufacture and use the same.

35 In the drawings 2 represents the base of the apparatus which may be formed of porcelain, or other suitable material; bolted to the base-plate 2 is a frame 3. Pivoted to the frame is the movable contact member 4, which is in electrical communication with the coil 12, and is provided with a carbon shunt contact piece 5, which is fixed to the end of the movable member. The movable contact member 4 is also provided with a 40 main contact face 6. The carbon contact piece 5, is so arranged that when the apparatus is in its closed position, it shall make contact with the stationary spring carbon shunt contact member 7, and the 45 contact face 6 shall also make contact with the stationary laminated main contact 8. The carbons 5 and 7 are secured to their supports by pins 26 which extend through openings in the carbon and by screws or bolts 50 27 passing through the supports and through

the carbon to the pins 26. This removes all metal from the faces of the carbons. These contact pieces 7 and 8 are at their bases bolted together and to the base 2 by the bolt 9 which forms one terminal *a* of the circuit. 60 The portion of this bolt 9 that passes through the laminæ is threaded, the threads serving to make a mechanical connection between the bolt and approximately each lamination of the laminæ, these laminations 65 being, of course, threaded to correspond with the thread of the bolt. Wrapped around a suitable spool 11 is a coil of wire or ribbon 12, whose convolutions are insulated from each other and one end of which 70 is secured to the base 2, by the bolt 13, which bolt forms the second terminal *b* of the circuit. The other end of the ribbon is fixed to the spool 11. This coil is resilient, and as the spool 11 is fixed to the pivoted movable contact member 4, the resiliency of the coil serves to normally keep this movable member in its retracted or open position. Extending through the center of the spool 11 is the core 14, which together with the 75 coil forms an electromagnet. This core 14 extends out beyond the sides of the frame 3. Pivoted to the frame 3 is the armature 15, which is of yoke form, having arms adapted to be attracted by the extending portions of 80 the core 14. This yoke 15 is provided with an adjustable stop 16, adapted to come in contact with the frame 3, and limit the backward movement of the armature. The lower portion of the yoke is weighted or made 85 sufficiently heavy to cause the arms of the armature to lie normally away from core 14. By adjusting the stop 16, this distance may be so regulated that a predetermined load 90 will energize the magnet sufficiently to attract the armature.

Pivoted to the base of the movable member 4, below its pivotal point, is the operating handle 10, which is extended beyond its pivotal point and is there forked and provided with cheeks 18, having enlarged openings or bearings 19, for the trunnions 20, of the friction roller 21. Within the frame 3, and secured to the base 2, is an incline 22, a seat 23, and a stop 24. When the handle 105 10 is pulled down, the roller 21 travels up the incline 22, and against the stop 24, where it seats itself upon the seat 23. This movement raises the lower end of the movable member 4, and causes the contacts 5 and 6 110

to come in contact with the fixed contacts 7 and 8. The stationary main contact member 8 is formed of laminæ of copper or other suitable conducting material having sufficient resiliency to give under the pressure of the movable contact face 6. The laminæ of which this contact is formed are all of the same length, are bent at substantially a right angle to form a base or support *c*, and 10 extend upwardly therefrom on a curved line each lamina extending from the support or base *c* on a higher plane than the preceding lamina; at their outer end they are again bent at substantially a right angle to form 15 short ridges *d*, which are separated from each other, and together give a level contact surface. I do not desire to limit myself to a base or support *c* formed by portions of the laminæ. The laminæ are preferably 20 held and supported by the bent guard-piece 25. The advantage of this separation of the contact ends of the laminæ are that they are less liable to become welded together. The effect of making the laminæ all of equal 25 length and curving them is greater resiliency and a more perfect contact surface. These laminæ taper from their base toward their ends, and at a short distance from their ends increase to their full width, as is shown 30 in the drawings. This tapering of the body and enlargement at the ends serves to more evenly distribute the strain of the contact on the laminæ, and to lessen the danger of injury to the elasticity of the member. 35 The operation is as follows: When it is desired to close the circuit the handle 17 is pulled down until the roller 21 seats itself against the stop 24 and on the seat 23, and the contacts 5—7 and 6—8 are brought together. The circuit is opened by a push upward on the handle 10, sufficient to unseat the roller 21, when the resiliency of the 40 spring 12 will then cause the movable member 4 to fly back. Should there be an over- 45 load on the circuit, the magnet being sufficiently energized, will cause the inner ends of the armature to move downwardly and

the outer ends upwardly, and so strike the handle 10 as to unseat the roller 21, from its seat 23 and break the circuit.

50

The advantages of my invention result from the simplicity of the apparatus and from the combination of parts which results in easy, rapid action; even contact between the contact pieces and freedom from liability of injury to the mechanism and contact faces.

55

Although I have shown the circuit opener provided with an automatic tripping device, I do not desire to limit myself thereto.

60

Having thus described my invention, what I claim and desire to secure by Letters Patent is—

1. In a circuit opener, the combination of a fixed contact member, a movable member, 65 an operating member, a roller loosely journaled in an enlarged bearing in the operating member, and a seat adapted to hold the roller.

2. In a circuit opener, the combination of 70 a fixed contact member, a movable contact member, a resilient, electro-magnet coil, the core of said coil extending through the same, and beyond the sides thereof, and constituting together with the coil, an electro-magnet, 75 and a pivoted armature within the magnetic field of the magnet and capable of engagement with the core, and means actuated by the movement of the pivoted armature to release the movable member whenever the 80 condition of the circuit becomes abnormal.

3. In a circuit opener, the combination of a fixed contact member, a movable contact member, an operating member pivoted to the movable contact member, a roller journaled in the operating member and a seat 85 adapted to hold the roller.

In testimony whereof, I have hereunto set my hand.

CHARLES C. BADEAU.
